UNITED STATES PATENT OFFICE.

WILLIAM H. TOWERS, OF NEW YORK, N. Y.

IMPROVEMENT IN SKELETON SKIRTS.

Specification forming part of Letters Patent No. 35,848, dated July 8, 1862.

To all whom it may concern:

Be it known that I, WILLIAM H. TOWERS, of the city, county, and State of New York, have invented a new and useful Improvement in Hoop-Skirts; and I do hereby declare that the following is a full, clear, and exact description of the same, reference being had to the accompanying drawings, making part of this specification.

Similar letters in the figures refer to corresponding parts.

In the hoop-skirt as now used it is attached to the person by a slim band or belt, which binds unpleasantly upon the body above the hips, from the fact of its slight bearing, enabling, moreover, the weight of the outside skirts to press the rear or bustle of the hoop-skirt out of shape.

Now, the nature of my invention consists in forming in one garment the hoop-skirt and a small bandage or corset in such a manner as to not only cause the latter to form a wide belt for the support of the hoop-skirt and skirts outside and a substitute for corsets, but also serve as a brace to support and always hold the bustle of the hoop-skirt in its proper position.

The skirt proper, A, may be made in the usual or most approved manner, and the small corset or brace B, with bustle attached, is made part of the same in lieu of the usual belt, being stiffened and braced to the person in front in the same manner as the usual corset, and consequently answering the same purpose. It, moreover, serves to uphold the bustle against the pressure of the skirts resting upon it, as before stated, by its braced forward part rising upward and acting as a stay to the whole extent of the bustle—both the side parts and back.

What I claim as new, and desire to secure by Letters Patent, is—

Combining a hoop-skirt and corset with bustle attached in one garment in the manner and for the purpose herein set forth.

WM. H. TOWERS.
